STEPHEN C. PRICE, OF LOUISIANA, MISSOURI, ASSIGNOR, BY DIRECT AND MESNE ASSIGNMENTS, TO P. R. B. PUMP COMPANY, OF HANNIBAL, MISSOURI, A CORPORATION OF MISSOURI.

DESIGN FOR AN OIL-CAN.

55,641.

Specification for Design.

Patented July 6, 1920.

Application filed January 2, 1920. Serial No. 349,036. Term of patent 14 years.

To all whom it may concern:

Be it known that I, STEPHEN C. PRICE, a citizen of the United States of America, residing at Louisiana, in the county of Pike and State of Missouri, have invented a new, original, and ornamental Design for Oil-Cans, of which the following is a specification, reference being had to the accompanying drawing, forming a part thereof, in which:

Figure 1 is a side elevation of the oil can embodying my invention,

Fig. 2 is a front view of the same.

The leading features of my design consist of the employment of a cylindrical body portion 3, and formed on the upper end of said

cylindrical body portion 3 is a semicircular member or portion 4. This semicircular portion 4 terminates in a conical portion 5, and secured to said conical portion 5 is a circular member 6, and secured to said circular member 6 is a downwardly depending flexible tubular member 7, said member 7 being provided on its lower end with a tubular member 8. The depending member 7 is provided with a curved portion 9.

I claim:

The ornamental design for an oil can as shown and described.

In testimony whereof I have signed my name to this specification,

STEPHEN C. PRICE.
